UNITED STATES PATENT OFFICE.

ABRAHAM NOVICK, OF NEW YORK, N. Y., ASSIGNOR TO F. L. SCHMIDT COMPANY, OF NEW YORK, N. Y., A CORPORATION OF NEW YORK.

ENVELOP-FASTENER.

1,201,335.

Specification of Letters Patent. Patented Oct. 17, 1916.

Application filed November 25, 1914. Serial No. 873,879.

To all whom it may concern:

Be it known that I, ABRAHAM NOVICK, a resident of the city of New York, county of Kings, and State of New York, have invented certain new and useful Improvements in Envelop-Fasteners, of which the following is a specification.

My invention relates to envelop fasteners, and has for its object the provision of cheap and strong means easily attachable to the outside of any envelop, for holding the flap to the body of the envelop.

To attain this object, I employ the devices shown in their preferred forms in the accompanying drawings, in which,

Figure 1 is a view of an envelop to which my improved fastener is attached showing the flap open. Fig. 2 is a similar view showing the flap closed and held by the fastener. Fig. 3 is a view of the metallic part of the fastener showing one form of the blank from which said metallic part is made. Fig. 4 is a view of a series of fasteners as they appear before they have been separated. Figs. 5, 6 and 7 are views of modified forms in which the metallic part of the fastener may be made showing various kinds of attaching means. Fig. 8 is a vertical section on the line A B of Fig. 1, in which the thickness of the parts sectioned are greatly exaggerated for clearness and Fig. 9 is a bottom view of the under side of the strip of paper to which the fastener is attached, showing the layer of gum on said strip.

The metallic member 1 is preferably of the shape shown in Figs. 3 and 4, having side prongs of the usual form and pointed projections 7 for attachment to a strip of paper 8, said strip 8 having a layer of gum 16 on the under side thereof. In place of the pointed rectangular projections 7, cuts may be made in metallic members as 10 and 12 to form triangular projections as 13 and 14 (Figs. 5 and 6). A circular projection as 15 in member 11, similar to the ordinary eyelet may be substituted for the projections 7, 13 or 14. To attach the metallic members as 1, 10, 11 and 12 to the gummed paper 8,

suitable projections as shown and described above are first made in said members, said projections then being passed through the paper 8 and bent to suitably engage the under side of said paper 8 as shown in Fig. 8, and by the dotted lines in Figs. 1 and 4.

The arrangement of a strip of gummed paper 8 with metallic members 1 attached thereto at regular intervals (Fig. 4) is a convenient method of making the fasteners when they are required in bulk, since the paper 8 may be separated into parts 6 by cutting at regular intervals as on dotted line 9 by a suitable machine and readily set on the outside of an envelop. The paper 8 is preferably quite heavy in comparison with the paper of the envelop to enable projections 7, 13, 14 and 15 to firmly grip said paper without danger of tearing.

It has heretofore been necessary to open the envelop to attach a fastener, and it has also been necessary to use a rather heavy paper for said envelop to give the fastening projections sufficient grip on the paper. It is obvious that the envelop need not be opened to attach my fastener as it is set entirely on the outside of said envelop without cutting into or penetrating the envelop paper, and it is also obvious that the grip of the fastener is entirely independent of the thickness or weight of the envelop paper. For strengthening the flap 3 of envelop 2, the piece 4 of heavy paper may be fastened to said flap 3, the hole 5 then being punched to allow the prongs of fastener 1 to pass through and be bent over as shown in Fig. 2, to hold said flap.

It is obvious that changes in the form of the metallic member, in the manner of fastening said member to the paper 8, such as the use of various forms of prongs and eyelets, and in the shape of the portion 6, may be made without departing from the scope of my invention.

What I claim is:

An envelop fastener adapted to be attached to the outside of the back of an envelop, comprising a single paper member

gummed on one side, a metallic member superimposed on the ungummed side of said paper member, projections formed from said metallic member, said projections passing through the middle of said paper member and clenched on the gummed side of said paper member for permanently securing the mid-

portion of said metallic member in intimate contact with the ungummed side of said paper member.

ABRAHAM NOVICK.
